UNITED STATES PATENT OFFICE

95,834

DESIGN FOR A STOCKING DISPLAY CABINET

Henry Janssen, Wyomissing, Pa., assignor to
Berkshire Knitting Mills, Wyomissing, Pa., a
corporation of Pennsylvania

Application February 13, 1935, Serial No. 55,386

Term of patent 14 years

To all whom it may concern:

Be it known that I, Henry Janssen, a citizen of the United States of America, residing at Wyomissing, in the county of Berks and State of Pennsylvania, have invented a new, original and ornamental Design for a Stocking Display Cabinet, of which the following is a specification, reference being had to the accompanying drawings, forming part thereof.

Figure 1 is a perspective view of the stocking display cabinet; the cabinet being shown as it appears with the windows open;

Fig. 2 is a perspective view of the display cabinet

illustrated in Fig. 1; the cabinet being shown with the windows closed;

Fig. 3 is a top plan view, on a reduced scale, of the cabinet of Fig. 2;

Fig. 4 is a view, in side elevation, of the device, as shown in Fig. 3; and

Fig. 5 is a view, in front elevation, of the cabinet, as shown in Figs. 3 and 4.

I claim:

The ornamental design for a stocking display cabinet as shown and described.

In testimony whereof I affix my signature.

HENRY JANSEN.
